UNITED STATES PATENT OFFICE.

WALTER BARNETT AND JAMES FLORENDINE, OF RUGBY, ENGLAND.

ROAD-SWEEPING MACHINE.

1,175,678.

Specification of Letters Patent.

Patented Mar. 14, 1916.

Application filed July 2, 1915. Serial No. 37,640.

To all whom it may concern:

Be it known that we, WALTER BARNETT and JAMES FLORENDINE, subjects of the King of Great Britain, residing at Rugby, Warwickshire, England, have invented certain new and useful Improvements in Road-Sweeping Machines, and of which the following is a specification.

This invention refers to a road sweeping machine of that type having a rotary brush at the rear of same and in contact with the road, which brush, operated from the road wheels, or axle of the machine, sweeps the mud or refuse onto a tray carried by a pivoted frame, and in which the tray, after receiving the refuse, is through mechanism coacting between the road wheels and the tray-supporting frame, raised to discharge its contents into a receptacle carried by the machine.

The present invention as hereafter particularly described and claimed refers to the provision of a two-part frictional clutch device brought into operation by a hand lever on the vehicle, the first part of said clutch device being in connection with the road wheels, while the second part is directly connected to the pivoted tray-carrying frame, which frame is counterbalanced by weights, so that when no refuse is on the tray it will remain in any position it is placed in. When the second part is engaged with the first part of the clutch device, which engagement is brought about by the operator, the tray-carrying frame is caused to turn about its axis, lift the tray, and so discharge its contents; the invention comprises means also whereby when brought to the discharging position, the frictional clutch device is automatically thrown out of operation and the refuse tray then remains in its discharging position until it is caused to return to its receiving position by a return motion of the said hand lever manipulated by the attendant. The refuse tray and its carrying frame being balanced as aforesaid, it would be subject to considerable vibrations or "chatter" should the second part of the clutch (which may conveniently consist of a metallic band) contact at any point with the first part of the clutch (which might consist of a drum) at a time when the two parts were intended to be out of engagement, and the invention therefore provides means for supporting the second part of the clutch away from the first part when the clutch is out of operation.

The invention will be described with reference to the accompanying drawings.

Figure 1 shows in side elevation, a machine according to the said invention with the refuse-tray in its receiving position, and Fig. 2 shows a similar view of the same machine with the refuse-tray raised and nearly approaching to its final discharging position. Fig. 3 shows in side elevation, certain parts of the mechanism which form the salient features of the invention, the illustration having the refuse-tray in its receiving position. Fig. 4 is a similar view with the refuse-tray in position about to be raised, 70 and Fig. 5 is a similar view of the parts showing the refuse-tray in a position corresponding to Fig. 2. Fig. 6 is a side elevation, and Fig. 7 is a plan view showing one of the counterbalance weights for the refuse-tray and its carrying frame. Fig. 8 is a side elevation, and Fig. 9 a vertical section of one of the frictional clutch devices, detached and drawn to a larger scale than the previous figures, there being one of such 80 clutch devices upon each side of the machine.

Referring more particularly to Figs. 1 to 5 of the drawings, the machine comprises a framework 1 supported toward the front part by bearings upon an axle 2, upon the ends of which two road wheels 3 are freely mounted, the bosses of the road wheels being fitted with ratchet devices as is common calculated to engage the axle 2 when the machine is moved forwardly in the direction of the arrow Fig. 1, so as to revolve the axle 2 with the road wheels but to leave the same stationary when the machine is moved rearwardly. The rear end of the machine is supported from the framework 1 by a trailer wheel 4, and at the rear the framework carries a revoluble brush 5 in contact with the road and driven in the direction of the arrow Fig. 1 by gear wheels 6, a chain 7 passing over a sprocket wheel mounted upon the axle 2 of the road wheels.

The refuse-tray 8 is carried by a frame comprising two levers 9 on each side of the machine, pivoted on stud axles 10, one on each longitudinal member of the framework 1. The levers 9 each extend forwardly beyond the stud axles 10, and each forward extension carries a counterweight 11, Figs. 3, 4 and 5, the forward part 12 of which, Figs. 110 3, 6 and 7, is knuckle jointed to the part 11 for a purpose hereafter described.

The weights 11 on the levers 9 are such that when the refuse tray is empty and is raised to the dotted position Fig. 1, it will remain in that position and will necessitate the application of a small amount of force as hereinafter described, in order to move the tray to its receiving position shown in full lines, at which position the tray will also remain stationary until again lifted.

10 Fixed to and extending from each of the levers 9, Fig. 3, is an arm 13, to the end of which a flexible connection or chain 14 is attached, the purpose of which will now be described.

15 Fixed near each end of the axle 2 within the longitudinal members of the frame 1 is a friction clutch wheel 15, see particularly Figs. 8 and 9, and extending around the periphery of each clutch wheel 15 there is an 20 annular flexible and elastic steel band 16 having on its interior upper surface, a leather or other lining 17 extending only partly around the flexible band 16.

25 Fixed to the exterior surface of the band 16 is a rigid pressure segment 18, and to one end of said segment 18 the opposite end of the chain 14 is fixed, which chain extends from one of the lever arms 13.

30 In conjunction with such friction clutches comprising the clutch wheels 15 and flexible bands 16, it is essential to provide means whereby, when the clutches are out of action, the friction bands 16 and their lining segments 17 shall be so supported that they 35 do not contact with the clutch wheels 15, or otherwise if the friction bands do so contact, the tray 8, being so nearly balanced, would be subject to vibrations or "chattering" when in its receiving position; such 40 supporting means consists of a cam-shaped foot 19, Figs. 8 and 9, fixed on the external periphery of the band 16, which foot 19 rests on a roller 20 when the clutch device is out of operation, the roller 20 being carried 45 from the main frame of the machine.

One end of the flange of the pressure segments 18 is formed with a forwardly extending foot 21 having an upturned end.

50 Mounted on a shaft 22, Fig. 3, extending across the machine and carried in bearings on the framework 1 is a hand lever 23, and near each end of the shaft 22 is fixed a crank 24, a link 25 extending from each crank to a slide rod 26 to which the end of 55 the link is pivoted. The slide rod 26 is carried in suitable guides from the main frame of the machine, and at its rear end it is fitted with a flanged roller 27, Fig. 8.

60 It will be understood without unnecessarily complicating and multiplying the drawings, that there are two clutch wheels 15, each clutch wheel having its co-acting parts, and in order to simplify the description, the operation of lifting the tray from its receiving to its discharging position and

then releasing the same from the lifting mechanism will be firstly described.

When the tray has gathered a supply of refuse the operator rocks the lever 23, Fig. 3, in the direction of the arrow, thereby 70 rocking the shaft 22 and consequently advancing rearwardly the slide rods 26, bringing the rollers 27 into pressure contact with the pressure segments 18. Simultaneously in each clutch mechanism (one on each side 75 of the machine), the braking surface or lining 17 of the band 16 engages the surface of its clutch wheel 15, and gradually the band 16 with the pressure segment 18 commences to revolve with the clutch wheel 15, 80 tensioning the chains 14, and thereby rocking the levers 9 about the stud axles 10 and carrying the tray 8 upward, as is shown at Fig. 5, from its normal position which is shown at Fig. 3.

85 As soon as the end of the pressure segment 18 passes from beneath the roller 27, Fig. 8, the tray will at that moment have arrived in its discharge position, and the operator who has been holding the hand lever 23 will feel that the roller 27 has left the segment 18 and will merely hold the lever 23 in position; so long as the operator holds the hand lever 23 with the rear angular end of the pressure segment 18 below 90 the roller 27, the refuse-tray 8 cannot descend, and in such position the refuse in the tray falls from the rear of the tray into a hopper 28 carried from the framework of the machine, passing into the hopper 28 by 95 way of a hinged back plate 29 on the tray 8, which hinged back plate during the rise of the tray is guided by a curved guide 30 mounted on the rear of the hopper 28; the hinged back plate 29 after passing the upper end of the curved guide 30 enters the hopper and forms a chute for the refuse. At the same time, so long as the operator holds the hand lever 23 so that the rollers 27 stand above the ends of the pressure segments 18, the refuse-tray 8 will be held in 100 its elevated position, while the effective friction of the band 16 on the clutch wheels 15 will cease and the said clutch wheels 15 will 105 revolve inoperatively within the band 16 110 while the refuse is discharged.

115 It will be here explained that the weights 11, 12 are shown in two parts, knuckle jointed together as before mentioned, in order that as the tray 8 reaches its discharge position, the weights shall not approach too closely to the road surface, and to this end, considering Fig. 5, the jointed ends 12 of the weights, as the tray reaches its discharging position, come against rollers 31 carried on 120 arms 32 from the framework of the machine, and so the weights assume a position as shown at Fig. 5.

125 When the refuse has been discharged from the tray 8 the operator reverses the move- 130

ment of the hand lever 23, Fig. 3. Considering Fig. 3 of the drawings, an arm 33 is pivoted at one end of the main frame 1, adjacent to the side of the machine upon which the hand lever 23 is located, and the opposite end of the arm 33 carries a flanged roller bearing upon the edge of the arm 13 or the lever 9, according to the position of the latter. The free end of the arm 33 is engaged by the lower end of a rod 34 capable of telescoping to a limited distance within a rod 35, the opposite end of which rod 35 is pivoted to the hand lever 23.

During the operative motion of the hand lever 23 in the direction of the arrow, Fig. 3, to cause the lift of the tray 8 to its discharge position, the rod 34 is inoperative, but when the hand lever 23 is moved in the opposite direction to the arrow in Fig. 3, that is just before the tray 8 arrives in the position shown at Fig. 5, after a period of motion of the hand lever 23 the rod 34 comes to the end of the bore in the rod 35, the telescopic action ceases, and as the hand lever 23 is further moved rearwardly, the rod 34 shares such movement, and the flanged roller on the end of the arm 33 acts to cause the turning of the levers 9 about their shaft 10, and thereby initiates the descent of the tray 8 from its discharge position to the position at Figs. 1 and 3.

In order to allow the rear end of the tray 8 to be sufficiently near the brush 5 to properly receive the sweepings and at the same time to permit the rear end of the tray to clear the brush during its lifting motion, a rear portion 36 of the tray 8, Fig. 3, is hinged to the main portion 8, and the rear portion 36 of the tray is turned up about its hinges prior to being lifted, by mechanical action of the hand lever 23, and the said hinged end 36 is maintained in its upturned position mechanically throughout the lifting, the discharge, and the descent of the tray. To effect this, a curved guide 37 is fixed to the framework on each side of the machine, and a lower guide 38 is provided, carried by arms 39 extending from a slide rod 40, operable in guides on the frame 1 and connected by a connecting rod 41 with the hand lever 23.

The lower end of each of the lower guides 38 is formed with a hook, and the forward face of said guide 38 is curved so that when its upper end is brought into conjunction with the curved guides 37, the lower guides 38 compose a continuation thereof.

The rear portion 36 of the tray has on each of its sides a flanged roller 42, which when the tray is in its receiving position as at Fig. 3, rests in the hook of the lower guide 38.

When the operator commences to move forward the hand lever 23 in the direction of the arrow Fig. 3, the first effect of such

movement is to bring the lower guide 38 forward from the position at Fig. 1 to the position at Fig. 4, thereby turning up the rear portion 36 of the tray 8, and during the succeeding movements of the parts, that is during the lifting and descent of the tray 8, the roller 42 on the rear portion 36 of the tray runs on the curved guides 38 and 37, and when the tray 8 arrives again at its receiving position, the lower guide 38 resumes the position shown at Figs. 1 and 3. Moreover it will be observed that upon the tray 8 arriving in the position of Figs. 1 and 3, the cam-shaped foot 19 on the band 16, Fig. 8, will again rest on the roller 20, while the flanged roller 27 of the slide rod 26 will contact with the upturned end of the foot 21 of the segment 18, and thus the flexible band 16 will be held so that its lining 17 does not contact with the clutch wheel 15.

Mechanism is provided so that when the vehicle is moved rearwardly by the traction member, such as the shafts 43, a rock shaft 44, Fig. 1, is rocked, and by means of cranks 45 thereon, links 46, and levers 47, depresses 90 the counterbalance weights 11, 12 and slightly raises the tray 8 so that it shall not contact with, for instance, the edge of a sidewalk.

What we claim as our invention and desire to secure by Letters Patent is:—

1. In road sweeping machines of the kind specified; the combination with road wheels, an axle carried thereby, a main frame supported by said axle, a rotary brush in contact with the road carried by said main frame and located at the rear of the machine, means for rotating said brush in a direction opposite to the travel of the machine, a refuse-receiving tray located rearward of the axle of said road wheels to receive refuse from said brush, and a counterbalanced tray-carrying frame pivotally mounted on said main frame to support said tray; of frictional clutches one on and near each end of said axle of said road wheels, each clutch comprising a revoluble member fixed to said axle, and a frictional member adapted when brought into pressure contact with said revoluble member to share 110 the angular motion of the latter, means operable by the driver to engage said clutches, connections between said frictional members of said clutches and said tray-carrying frame to cause said frictional members of 115 said clutches when engaged to turn said tray-carrying frame about its pivotal axis to bring said tray into its discharge position, means for automatically throwing said tray-carrying frame about its pivotal axis to bring said tray into its discharge position, means for automatically throwing said tray-carrying frame about its pivotal axis to bring said tray into its discharge position, means for automatically throwing said tray-carrying frame about its pivotal axis to bring said tray into its discharge position, and means operable by the driver for returning said tray to its receiving position.

2. In road sweeping machines of the kind specified; the combination with road wheels,

- an axle carried thereby, a main frame supported by said axle, a rotary brush in contact with the road carried by said main frame and located at the rear of the machine, means for rotating said brush in a direction opposite to the travel of the machine, a refuse-receiving tray located rearward of the axis of said road wheels to receive refuse from said brush, and a counterbalanced tray-carrying frame pivotally mounted on said main frame to support said tray; of frictional clutches one on and near each end of said axle of said road wheels, each of said clutches comprising a revolute member fixed to said axle and a frictional member adapted when brought into pressure contact with said revolute member to share the angular motion of the latter, means for supporting said frictional member, means operable by the driver for bringing said frictional member into pressure contact with said revolute member to cause said frictional member to revolve therewith, a direct mechanical connection between said frictional member of said clutch and said tray-carrying frame to cause said clutch members when engaged to turn said tray-carrying frame about its pivotal axis to bring said tray to its discharge position, means to automatically disengage said frictional member from said revolute member of said clutch when said tray arrives in its discharge position, and means operable by the driver for returning said tray to its receiving position.
3. In road sweeping machines of the kind specified; the combination with road wheels, an axle carried thereby, a main frame supported by said axle, a rotary brush in contact with the road carried by said main frame and located at the rear of the machine, means for rotating said brush in a direction opposite to the travel of the machine, a refuse-receiving tray located in front of said rotary brush to receive refuse, and a counterbalance tray-carrying frame pivotally mounted on said main frame rearward of said axle to support said tray; of frictional clutches one on and near each end of said axle of said road wheels, each of said clutches comprising a friction disk fixed to said axle, an annular friction band loosely surrounding said friction disk, a segmental friction lining on said band calculated to be brought into friction contact with said disk, a projecting pressure segment fixed exteriorly on said friction band, a pressure roller, a carrying member for said roller, means for supporting said carrying member from said main frame, means operable by the driver to cause said roller to act against said pressure segment to engage said annular band with said friction disk to cause said band to share the angular motion of said disk, a mechanical connection extending directly

between said annular friction band and said tray-carrying frame to turn said tray-carrying frame about its pivotal axis during the engagement of said clutch members until the end of said pressure segment passes said pressure roller at the moment said refuse-tray is in its discharge position to thereby release said frictional clutch members, and means operable by the driver for returning said tray to its receiving position.

4. In road sweeping machines of the kind specified; the combination with road wheels, an axle carried thereby, a main frame supported by said axle, a rotary brush in contact with the road carried by said main frame and located at the rear of the machine, means for rotating said brush in a direction opposite to the travel of the machine, a refuse-receiving tray located rearward of the axis of said road wheels to receive refuse from said brush, and a counterbalanced tray-carrying frame pivotally mounted on said main frame to support said tray; of frictional clutches one on and near each end of said axle of said road wheels, connections between said clutches and said tray-carrying frame to cause said clutches when engaged to turn said tray-carrying frame about its pivotal axis to bring said tray to its discharge position, means operable by the driver for bringing said clutches into engagement to bring said tray to its discharge position, means to automatically disengage said clutches when said tray arrives at its discharge position, means operable by the driver for returning said tray to its receiving position, said means comprising an arm pivoted to the main frame, a roller on the free end of said arm calculated to act against the tray-carrying frame, and a telescopic rod connected at one end to said free roller-carrying end of said arm and at the other end to said hand lever to force said tray-carrying frame from its discharge position to its receiving position by the rearward movement of said hand lever by said driver.

5. In road sweeping machines of the kind specified; the combination with road wheels, an axle carried thereby, a main frame supported by said axle, a rotary brush in contact with the road carried by said main frame and located at the rear of the machine, means for rotating said brush in a direction opposite to the travel of the machine, a refuse-receiving tray located in front of said rotary brush to receive refuse, and a counterbalanced tray-carrying frame pivotally mounted on said main frame rearward of said axle to support said tray; of frictional clutches one on and near each end of said axle of said road wheels, each of said clutches comprising a friction disk fixed to said axle, an annular friction band loosely surrounding said friction disk, a segmental friction lining on said band calculated to be brought into friction contact with said disk, a projecting pressure segment fixed exteriorly on said friction band, a pressure roller, a carrying member for said roller, means for supporting said carrying member from said main frame, means operable by the driver to cause said roller to act against said pressure segment to engage said annular band with said friction disk to cause said band to share the angular motion of said disk, a mechanical connection extending directly

friction lining on said band calculated to be brought into friction contact with said disk, a projecting pressure segment fixed exteriorly on said friction band, a pressure roller, 5 a carrying member for said roller, means for supporting said carrying member from said main frame, means operable by the driver to cause said roller to act against said pressure segment to engage said annular band with 10 said friction disk to cause said band to share the angular motion of said disk, a flexible connection between said annular friction band and said tray-carrying frame to turn said tray-carrying frame about its pivotal 15 axis during the engagement of said clutch members until the end of said pressure segment passes said pressure roller at the moment said refuse-tray is in its discharge position to thereby release said frictional 20 clutch members, means for supporting said annular friction band away from the periphery of said friction disk when in its normal position, comprising a cam-shaped foot fixed on the external periphery of said band, 25 a roller carried from said main frame upon which said foot rests when said band is in its normal inoperative position, a forwardly extending foot located at the end of said projecting pressure segment on said band, 30 an upturned end to said foot to provide an abutment to bear against said pressure roller when the latter is in its inoperative position to hold said annular friction band away from said friction disk, and means operable 35 by the driver for returning the refuse-receiving tray to its receiving position.

6. In road sweeping machines of the kind specified; the combination with road wheels, an axle carried thereby, a main frame supported by said axle, a rotary brush in con-

tact with the road carried by said main frame and located at the rear of the machine, means for rotating said brush, a refuse-receiving tray located in front of said rotary brush, a hinged rearward extension 45 of said tray, and a counterbalanced tray-carrying frame pivotally mounted on said main frame to support said tray; of frictional clutches one on and near each end of said axle of said road wheels, a hand lever, 50 mechanical connections operable by said hand lever to turn up the hinged rearward extension of said refuse-tray, mechanical connections operative by said hand lever to engage said frictional clutches, flexible connections between said frictional clutches and said tray-carrying frame to cause said clutches when engaged to turn said tray-carrying frame about its pivotal axis to discharge the refuse from said refuse-tray, 55 means for retaining the hinged rearward extension of said refuse-tray in its upturned position during the rise of said tray from its receiving to its discharging position, means for automatically throwing said frictional clutches out of operation when said tray arrives at its discharge position, means 60 for returning said tray to its receiving position by a reverse operation of said hand lever, and means for supporting the hinged 65 rearward extension of said refuse-tray in its extended receiving position.

In witness whereof we have hereunto set our hands in the presence of two witnesses.

WALTER BARNETT.
JAMES FLORENDINE.
